US00D914667S

(12) **United States Design Patent** (10) **Patent No.:** **US D914,667 S**
(45) **Date of Patent:** **** Mar. 30, 2021**

(54) **DISPLAY DEVICE**

(71) Applicant: **Innovative Vending Solutions, LLC**,
Clayton, NJ (US)

(72) Inventors: **Gregory Ruggiero**, Sewell, NJ (US);
Richard Ruggiero, Sewell, NJ (US);
Jonathan M. Ruggiero, Turnersville,
NJ (US)

(73) Assignee: **INNOVATIVE VENDING
SOLUTIONS, LLC**, Clayton, NJ (US)

(**) Term: **15 Years**

(21) Appl. No.: **29/719,902**

(22) Filed: **Jan. 8, 2020**

(51) LOC (13) Cl. **14-02**

(52) U.S. Cl.

USPC **D14/307**

CLAIM

The ornamental design for a display device, as shown and described.

DESCRIPTION

FIG. 1 is a front right top perspective view of a display device, showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line portion of the figure drawings is included to show portions of the article that form no part of the claimed design.

1 Claim, 6 Drawing Sheets
